UNITED STATES PATENT OFFICE.

JAMES PIERCY, OF BLOOMFIELD, NEW JERSEY.

IMPROVEMENT IN WASHERS FOR PAPER-PULP.

Specification forming part of Letters Patent No. 34,214, dated January 21, 1862.

To all whom it may concern:

Be it known that I, JAMES PIERCY, of the town of Bloomfield, in the county of Essex and State of New Jersey, have invented certain Improvements in Washers for Paper-Pulp; and I do hereby declare the following to be a full and exact description thereof, reference being had therein to the drawings which accompany this specification and make part of the same.

The nature of my invention consists in a discharge of the water from an open end in a washer through the side of the tub or vat in which the pulp is beaten by a new way of opening and closing the valve.

In the drawings, Figure 1 is a perspective view of the vat with the washer in place. Fig. 2 shows that side of the valve board or plate which goes to the side of the vat. Fig. 3 is an edge section of the vat, the plate, and the washer. Fig. 4 is the side of the board or plate that goes against the washer. Fig. 5 is an upper edge view of the plate and its slides.

The same letters refer to the same parts in each figure.

The letter A shows the vat or tub; B, the washer; C, the valve board or plate; S, the valve or openings for the discharge of the water. The journal *a* on the shaft *b* of the washer B at the end next the side of the vat or tub is held in a bearing *e*, which is permanently fixed to the upper edge of the board or plate C, so that when the journal-boxes *e* are raised by means of the racks *f*, pinions *g*, and crank *h* the box on the side next the side of the vat or tub will carry up with it the board or plate C, and so bring the lower portion *k* of the plate C over the opening S in the side of the tub A, the pressure of the pulp being sufficient to make a tight joint between the plate and the tub.

One end of the washer B is closed. The end next the side of the vat is open and has a circular rim supported by arms. Upon the circular rim *m* there is a projection *i*, which corresponds with a projection, also marked *i*, on the valve board or plate C. The projection *i* on the rim *m* of the washer B when the washer revolves rubs against the projection *i* on the board or plate C, and undue leakage at the joint is prevented by placing a strip of water-tight or other material *v*, as wide as the two projections *i* put together, around the lower part of the circle *i* on the rim *m* of the washer and the semicircle *i* on the plate, with its ends fast to pins on the upper part of the plate C, as shown in Fig. 4.

Two slides *n* are made fast to the sides of the vat or tub A, the edges of which are V-shaped, as shown in Fig. 5, or square, as the case may be, to which the ends of the board C are made to correspond and fit, the pieces *n* being holders and guides to the plate C on its being hoisted from or lowered into the pulp in the vat.

Motion to the washer is given from the main shaft *w* of the beater, as the case requires provision being made to allow the washer to rise out of gear when it is lifted by the racks and pinions.

I do not claim a side discharge of the water, nor a washer with one closed and one open end.

What I claim is—

The combination of the washer B, its journal-box *e*, and the valve-board C, under a method of construction and operation substantially as above described.

JAMES PIERCY.
